UNITED STATES PATENT OFFICE.

WILLIAM T. MERSEREAU, OF SOUTH ORANGE, NEW JERSEY.

DESIGN FOR A JAPANESE TEA-STAND.

SPECIFICATION forming part of Design No. 18,835, dated January 1, 1889.

Application filed October 11, 1888. Serial No. 287,865. Term of patent 3½ years.

To all whom it may concern:

Be it known that I, WILLIAM T. MERSEREAU, a citizen of the United States, residing at South Orange, Essex county, and State of New Jersey, have invented and produced a new and original Design for a Japanese Tea-Stand, of which the following is a specification, reference being had to the accompanying drawing, forming a part thereof.

10 The accompanying drawing represents a perspective view of my newly-designed Japanese tea-stand.

A represents the stand proper, the legs or supports of which flare or spread out near their base, as shown, and the same have connection at or near their center by rods crossing each other at right angles. Said legs or supports for a small space between their base and central point of connection and from 15 their upper ends to said central point of connection are represented as twisted, substantially as shown. At or near one side of the top of said stand A, arranged substantially as shown, projects a crane-shaped structure consisting of a vertical rod, b, across the upper 20 end of which extends a rod, a, one end pro-

jecting immediately above the center of said stand A, from which depends a rod, d, provided at its lower end with a cross-bar turned up at opposite ends in the form of hooks, as 30 shown. The opposite end of said rod a has a right-angle connection with the vertical rod b a short distance above the top of stand A by rod c c, forming a square or oblong, as shown. The said vertical rods b and c, a short distance 35 from their point of connection with the horizontal rod or bar c and a corresponding space from their upper ends, are represented as being twisted, to correspond with the legs or supports of the stand A. 40

What I claim is—

The design for a Japanese tea-stand herein shown and described, the same consisting of a stand arranged and ornamented substantially as shown, and a crane-shaped structure 45 projecting from one side of said stand, arranged in its relation to said stand and ornamented as shown.

WILLIAM T. MERSEREAU.
